(57) **CLAIM**

The ornamental design for a tire tread band, as shown and described.

DESCRIPTION

FIG. 1 is a front elevational view of a tire tread band showing my new design, it being understood that the tread pattern repeats circumferentially throughout the outer circumference;

FIG. 2 is a perspective view of one side of the tire tread band shown in FIG. 1; and,

FIG. 3 is a side elevational view of one side of the tire tread band shown in FIG. 1, the opposite side being of identical appearance.

In the drawings, the broken lines show the sidewall of a pneumatic tire only and form no part of the claimed design.
